UNITED STATES PATENT OFFICE.

ARTHUR J. JUDGE, OF ST. LOUIS, MISSOURI.

SELF-LEVELING STEP-LADDER.

1,117,496.

Specification of Letters Patent. Patented Nov. 17, 1914.

Application filed August 11, 1913. Serial No. 784,016.

To all whom it may concern:

Be it known that I, ARTHUR J. JUDGE, a citizen of the United States, and a resident of the city of St. Louis and State of Missouri, have invented a new and useful Improvement in Self-Leveling Step-Ladders, of which the following is a specification.

This invention relates to step-ladders of the type having a ladder section and legs or 10 props pivoted thereto for supporting the ladder independently of a fixed support, such as a wall.

The object of this invention is a four-legged step-ladder which will adapt itself 15 automatically to any unevenness in the ground or other surface upon which it may be set up.

The invention consists in a step-ladder provided with props or legs pivoted to the 20 ladder portion and rigidly braced against sidewise movement, the two legs being freely 25 slideable up and down relatively to their pivots, and connected to each other in such manner that when one slides up the other slides down an equal distance, whereby they 30 accommodate themselves to uneven supporting surfaces.

Further objects of the invention appear in 35 connection with the description of the embodiment thereof shown in the accompanying drawings, and in what the invention consists is particularly pointed out in the appended claims.

In the drawings, in which like characters 40 designate like parts wherever used, Figure 1 is a side view of a step-ladder embodying the invention; Fig. 2 is a back view of the same; Fig. 3 is an enlarged view of the top portion of a slideable leg, showing the pivot 45 fittings and equalizing gearing; Fig. 4 is a side view of the same looking from the inner side of the leg; Figs. 5 and 6 are cross sections of a sliding leg taken on the lines 5—5 and 6—6, respectively, looking in the 50 direction of the arrows; Fig. 7 is an enlarged cross section through the sliding legs taken on the line 7—7 in Fig. 2, looking in the direction of the arrows, and showing the gears and shaft in plan view; Fig. 8 is 55 an enlarged cross section through a sliding leg taken on the line 8—8 in Fig. 2, looking in the direction of the arrows; and Fig. 9 is a view of a modification of the construction shown in Figs. 3 to 6, whereby the legs can 60 be clamped in adjusted position.

Referring to the drawings, the step-lad-

der comprises a ladder section 11 having steps 12, and a platform 13 rigidly secured to the ladder portion at its top. The legs or props 14 are slideable in metal boxings 15 which are pivoted to brackets 16 secured below the platform. The lower ends of the legs slide through straps 17 at the ends of a cross-bar 18. This cross-bar is supported and braced from the boxings 15 by means of 60 diagonal slats 19 securely fastened at their upper ends to lugs 20 formed integral with the boxings 15. A cross rod 21 connects the lugs 20 of the two boxings and braces the top ends of the sliding legs against sidewise 65 movement.

The upper ends of the props are fitted with toothed racks 22 which slide in the boxings. One of these racks faces to the front and the other faces to the rear, and they mesh with the opposite sides of two pinions 23 fixed to the ends of the horizontal rod 24 journaled in the two boxings. By reason of this arrangement, when there is no weight on the step-ladder one prop 70 may be raised and the other lowered simultaneously and by equal amounts, thereby enabling the step-ladder to adjust itself to uneven floors or other surfaces upon which it may be set up. Any weight upon 75 the step-ladder tends to cause both props to slide upward in the boxings, and, as the racks engage on opposite sides of the pinions, any simultaneous movement of both props upward is thereby prevented, what- 80 ever the relative position of the two props with respect to each other.

The boxing 15 may be provided with a clamp bolt 26 and lever nut 27, as shown in Fig. 9, if it is desired to clamp the sliding 95 legs from movement after the step-ladder is set up. In views 1, 2, 3, 4 and 6, rivets 25 are shown for retaining the sliding legs in the boxings instead of the clamp bolt 26, because the clamp bolt is found not to be 100 necessary to the successful use of the device.

It is evident that changes in the details of construction of my device may be made without departing from my invention, and I do not restrict my invention to the embodiment thereof shown and described herein.

What I claim as my invention is as follows:

1. A self-adjusting device for parallel 110 slideable legs, guides for said legs, racks carried by said legs on opposite sides thereof,

and pinions meshing with said racks, said pinions being secured to a transverse shaft mounted in said guides.

2. A self-leveling step ladder comprising
5 a rigid ladder, swinging guides pivoted to
said ladder near its top, two props slidably
arranged in said guides, racks secured to
said props on opposite sides thereof and a
shaft rotatably mounted in said guides and
10 carrying pinions at its ends meshing with
said racks respectively, and means for re-
taining said props in said guides.

3. A self-leveling step ladder comprising
a rigid ladder, a swinging frame pivoted to
15 said ladder near its top, two props slidably

arranged in said frame, said frame having
cross braces for the lower ends of said
props, a rack secured to the front edge of
one of said props, a similar rack secured to
the back edge of the other prop, and a shaft 20
rotatably mounted in said frame and carry-
ing pinions at its ends meshing with said
racks respectively.

Signed at St. Louis, Missouri, this 8th
day of August, 1913.

ARTHUR J. JUDGE.
